ABSTRACT

A tube having one end for insertion through a hole in a boat, which end has concentric bags inflatable on the end thereof, and which bags when inflated are pulled over the hole with the water pressure holding the bags in position over the hole; and expandable legs connected to the tube and movable longitudinally to contact the inside of the boat and to hold the inflated bags and tube in sealing position.

DEVICE FOR TEMPORARILY SEALING HOLES IN BOATS

BACKGROUND OF THE INVENTION

The number of small boats used for pleasure and commerce are constantly on the increase. New boat designs have made the hulls of the boats considerably lighter, as well as more fragile. Further boats are now being used in areas that have rocks, and other articles in the water, that can cause holes to be punched in the side of the boats. Such small boats do not have the bilges pumping capabilities, that will cope with water entering through a relatively small hole in the hull of the boat, and thus prevent the boat from rapidly sinking. Thus a small hole knocked in the side of a boat can oftentimes cause the boat to sink and result in loss of life as well as a total loss of a rather expensive boat, including all electronic gear that is normally on such boats.

Thus it is advantageous to have a device for temporarily sealing holes in boats, which device can be quickly, easily and reliably used and that has an inflatable end that adjusts to seal holes of many different sizes, and that has means for holding the sealing device in position until the boat can be returned to safe moorage.

SUMMARY OF THE INVENTION

In a preferred embodiment of this invention, a tube has a first inflatable gas bag connected to one end, with a second inflatable gas bag positioned inside of the first gas bag. A gas source, such as a CO₂ cartridge, is secured to the tube at preferably the other end of the tube for passing gas through the tube upon demand and inflating the first and second gas bags. The gas bag end of the tube has first and second valves, that control the gas entering the bags in a manner that both bags are inflated correctly. A retainer housing retains the gas bags in the non-inflated condition in a small folded-up condition with a small diameter that allows the end of the tube and retainer to be inserted through a rather small hole in the boat, without damage to the bags. When the retainer housing is then removed, exposing the bags, the bags are then inflated in the water outside the boat. The gas bags when inflated cover the hole and are held in position, by the outer water pressure, thereby sealing the hole in the boat.

Since the boat can be moved with the sealing device in position, the sealing device is subjected to the movement of water along the side of the boat. This could require that a person grasp and pull on the other side of the tube to retain the gas bags in position. However to avoid this, expandable legs are positioned along the length of the tube, and expand outwardly at an acute angle to contact the inside of the hull and hold the gas bags in position over the hole.

The inner and outer gas bags, not only provide increased stability of the bags in the compressed condition at the hole that is being sealed, but also provide a safety factor should the outer bag be punctured. With the outer bag being punctured, the inner bag then forms the complete seal and additionally if the outer bag is punctured through contact with sharp edges of the boat hull around the hole, then the punctured bag forms a resilient cover over the jagged edges of the

hole, allowing the inner bag to maintain the seal and be protected by the outer bag.

It is therefore an object of this invention to provide a new and improved device for temporarily sealing holes in boats.

Other objects and many advantages of this invention will become more apparent upon a reading of the following detailed description and an examination of the drawings, where like reference numerals designate like parts throughout and in which;

FIG. 1 is a side elevation view of the complete sealing device in collapsed condition.

FIG. 2 is an enlarged sectional view taken on line 2-2 of FIG. 1.

FIG. 3 is a similar sectional view, but with the inflatable head extended.

FIG. 4 illustrates the initial insertion of the device through a hole in the boat structure.

FIG. 5 illustrates the fully sealed position of the device.

Referring now to the drawings, the device for temporarily sealing holes 10 has an elongated tube 12 that extends substantially the entire length of the device. Positioned on one end 42 of the tube 12 is a valve cylinder 36 on which an outer inflatable gas bag 20 and an inner inflatable gas bag 22 are secured. The outer bag 20, is held in sealed position by a retainer ring 40 in a circumferential groove in the outer surface of valve cylinder 36. The end of the bag 22 is held by the resilient retainer 38 in a similar circumferential groove in the valve cylinder 36. A valve opening 24, is covered by a flapper check valve member 26 that is retained in position by a retainer 28. A second valve 30, has a ball spring check valve arrangement, wherein ball 32 is biased by spring 34. Spring 34 requires a slight pressure differential of the inflating gas to open the valve and inflate the bag 22.

An outer cylindrical housing 14, is slidably positioned over the end of the tube 12, and rides on cylindrical block 44 secured to the outer surface of the tube end 42. The cylindrical housing 14, encloses the first and second air bags in the manner illustrated, and has an end cap 16. A longitudinal slot 48 with hook end slots 50, co-act with the retainer pin 52 secured to block 44, for positioning and holding the cylindrical housing 14, in an extended position, whereby the non-inflated gas bags 20 and 22 are enclosed as illustrated in FIG. 2, and in a retracted position whereby the gas bags are exposed, as illustrated in FIG. 3.

Expandable legs 10, are pivotally supported by holder 56 that maybe threadably positioned on threads 58 on the tube 12. The legs 54 expand radially outward to an acute angle in the direction of the gas bags. Wing nut 60 locks the holder 56 in position. The holder 56 can either threadably engage threads 58 or be slidably movable therealong.

A gas source means, such as a known CO₂ cartridge 18, is positioned on the other end of the tube 12 and is operable in the known manner, such as by pulling a chain (not shown) or by other known valving arrangements, to cause the gas to pass from the cartridge 18 and expand through tube 12 to inflate the gas bags 20 and 22.

In operation, when a hole is discovered in a boat, such as in the hull 100 of the boat, then the housing 14 end of the device 10 is inserted through the hole 102, as in FIG. 4. The housing 10 is then rotated around pin

52, and is pulled toward the other end, to the retracted position exposing the bags 20 and 22. The CO₂ cartridge 18 is then punctured allowing gas to pass through the channel 62 of the tube 12 and initially through opening 24 of valve 26 into gas bag 20. This initial gas release, immediately starts the inflating of the bag 20. In this inflation, the bag 20 expands outwardly into the water, encountering a water pressure resistance. This coupled with the normal pressure involved and required in expanding any gas bag, causes the gas pressure to increase in the valve cylinder 34 to the extent that it overcomes the force of spring 34, allowing bag 22 to inflate. The pressure differential between the two valve openings, and the pressure of the gas entering the system, is such that both bags are inflated concentrically with one bag being positioned inside the other bag and with a gas space therebetween. The other end of the tube 12 is then pulled, while the bags 20 and 22 are being inflated, correctly positioning the bags over the hole 102. Water pressure on the outside of the hull 100 additionally forces the bags 20 and 22 over the hole 102. To assure that the device will remain in this position, the legs 54 are expanded outwardly by moving the holder 56 down the tube 12, to the point where the end 104 of the legs contact the inside surface of the hull 100. Wing nut 60 is then threadably moved downwardly against the holder 56 holding and locking the legs in position, as in FIG. 5.

In this condition, the boat may then be moved to safer waters or to a mooring where the hole in the boat 30 is repaired under safe conditions.

Having described my invention, I now claim:

1. A device for temporarily sealing holes in boats comprising,

a tube having an end for inserting through a hole in 35

a boat,

said tube end having a first inflatable gas bag secured thereto,

a second inflatable gas bag positioned inside of said 40 first gas bag and being connected to the end of said tube,

means for pressurized gas inflating said first and second air bags,

and said tube end having valve means for selectively passing pressurized gas to each of said first and second bags, inflating both of said bags. 45

2. A device for temporarily sealing holes in boats as claimed in claim 1 wherein,

said tube end has a housing, for enclosing said first and second gas bags in the non-inflated condition. 50

3. A device for temporarily sealing holes in boats as claimed in claim 2 wherein,

said housing has cylindrical and relatively narrow di-

ameter for inserting through a hole in a boat, and 55

having a releasable end that allows said tube end and said inflatable bags to be passed out through

said open end and to be inflated.

4. A device for temporarily sealing holes in boats as

claimed in claim 3 wherein,

said housing is slidable on said tube,

means connected to said tube and said housing for

holding said housing in extreme slidable positions, and said positions including a first position wherein

said housing encloses said gas bags, and in a second position wherein said housing is moved to expose

said gas bags.

5. A device for temporarily sealing holes in boats as claimed in claim 1 wherein,

pressurized gas means conducts gas through said valve means including a first check valve for passing gas into said first inflatable gas bag,

a second check valve, for passing gas to said second inflatable gas bag,

and said second valve being opened only after a certain gas pressure exists in the end of said tube, whereby said first gas bag is substantially inflated before gas is inserted into said second gas bag.

6. A device for temporarily sealing holes in boats as claimed in claim 5 wherein,

said second valve is positioned in the end of said tube,

said second gas bag, encircles the end of said tube and is secured to the outer circumference of said tube,

said first valve is positioned in the side of said tube outside said second bag,

and said first bag is sealably secured to the outer circumference of said tube and enclosing said first valve.

7. A device for temporarily sealing holes in boats as claimed in claim 1 wherein,

said pressurized gas means comprises a source of gas positioned at the other end of said tube.

8. A device for temporarily sealing holes in boats as claimed in claim 1 wherein,

said tube has expandable legs positioned along the length of said tube, which legs pivot outwardly to an acute angle in the direction of said inflatable bags,

said expandable legs are movable along the length of said tube,

and means for holding said legs at a given position along the length of said tube whereby said legs expand outwardly to contact the inside of a boat to hold the inflated bags in the hole of said boat sealing said hole.

9. A device for temporarily sealing holes in boats as claimed in claim 8 wherein,

said tube is threaded,

said legs have a threaded member for threadably engaging said threads on said tube,

and said holding means comprises wing nut.
